DESIGN FOR A DECORATIVE ILLUMINATING DEVICE OR SIMILAR ARTICLE

Leo Pollock, New York, N. Y.

Application May 20, 1940, Serial No. 92,470

Term of patent 3½ years

To all whom it may concern:

Be it known that Leo Pollock, a citizen of the United States and resident of New York city, in the county of New York and State of New York, has invented a new, original, and ornamental Design for a Decorative Illuminating Device or Similar Article, of which the following is a specification reference being had to the accompanying drawing forming part thereof, in which,

Fig. 1 is a front view in perspective of a decorative illuminating device embodying my new design; and

Fig. 2 is a side view thereof. The representations of the side bulbs shown in Fig. 1 have been omitted for convenience of illustration.

The dominant features of my design reside in the portions shown in full lines.

I claim:

The ornamental design for a decorative illuminating device or similar article, substantially as shown and described.

LEO POLLOCK.
